MUSICAL RECORDER

George H. Frost, Kent, Ohio, assignor to Diemolding Corporation, Canastota, N.Y., a corporation of New York, and Frank H. Douglas, Shaker Heights, Ohio

Filed Aug. 20, 1969, Ser. No. 18,774

Term of patent 14 years

Int. Cl. D17—02

U.S. Cl. D56—1

FIG. 1 is a top plan view of a recorder embodying my new design;

FIG. 2 is a right side elevation thereof; and

FIGS. 3, 4, 5 and 6 are transverse sections taken respectively on lines 3—3, 4—4, 5—5 and 6—6 of FIG. 1.

I claim:

The ornamental design for a musical recorder, substantially as shown.
